EGG CARTON

Carl H. Lowe, Chicago, Ill., assignor to Self-Locking Carton Co., Chicago, Ill., a corporation of Illinois

Application November 21, 1935, Serial No. 50,816

2 Claims. (Cl. 229—29)

The present invention pertains to cellular cartons of the type customarily employed in the packaging of eggs and other fragile products and has particular reference to an improvement 5 in the cell structure of such containers.

A cellular carton which has met with considerable approval in the industry is described in Troyk U. S. Reissue Patent No. 18,922. This carton and others in the industry consist of two 10 rows of cells each containing six individual compartments, making the capacity of the carton an even dozen. In the merchandizing of eggs, particularly when the price of eggs is high, there is a demand for half-dozen capacity cartons. 15 To meet this demand, efforts have been made to provide a suitable severable carton which may be broken in half. The greatest problem in providing such a carton is in the proper arrangement of the cross partitions which divide the 20 carton into the individual cells.

A principal object of the present invention is the provision of an improved cushion-forming divisible carton.

An additional object is to provide an effective 25 cross partition arrangement for cellular cartons.

Still another object is the provision of a cushion-forming carton having an upraised longitudinal partition and auxiliary cross partitions struck from the walls of the carton and adapted 30 to lock with the longitudinal partition.

These and other objects will be evident from a consideration of the following description and by reference to the accompanying drawing in which

Fig. 1 is a top view of a carton constructed in accordance with my invention;

Fig. 2 is a fragmentary side view of the carton shown in Fig. 1 and displaying the auxiliary cross partition;

Fig. 3 is a fragmentary sectional view, taken along line 3—3 of Fig. 1;

Fig. 4 is a cross sectional view, taken along line 4—4 of Fig. 1; and

Fig. 5 is a view of the blank from which the 45 carton is constructed.

As shown in the drawing, the carton is formed from a single blank cut, scored and folded to form in the order named, a cover locking strip 10, a top 11, a rear wall 12, a rear bottom and longitudinal partition-forming section 13, a front bottom and longitudinal partition-forming section 14, a front wall 15, cross partitions 16 hinged to the front wall by means of the triangular hinged members 17, and a cover locking strip 18 hinged 55 to the opposite side of the cross partitions by

means of the triangular hinged members 19. The various elements specified are separated from each other by score lines running longitudinally of the carton. In manufacture, the attaching strip 18 is folded over and secured to the rear 5 wall by gluing.

The carton is erected by folding the cross partitions 16 into vertical position and pressing the front and rear bottom and longitudinal partition-forming section upwardly into an inverted V-shape as shown in Fig. 4, the openings 20 in the bottom and longitudinal partition-forming section receiving and forming an interlock with the hooks 21 on the lower portions of the cross partitions. The upper portions of the cross partitions 15 are provided with upwardly extending brace members 22 which engage the cover of the carton and form a support therefor.

The cross partitions 16 may be spaced substantially evenly throughout the carton. Adjacent the central cross partition the entire blank is perforated as shown along the line 23, so that it is possible to pull the carton apart along this perforated line after the carton is set up and filled with eggs. When the carton is so separated into 25 two parts, it is necessary to provide the end of the open section of the carton with some means for preventing the eggs in the end cells from falling out. In accordance with my invention, this is done by striking a portion 24 from the rear 30 wall and a corresponding portion 25 from the front wall, it being understood that the auxiliary cross partitions 24 and 25 are cut from the rear and front walls, respectively, along three sides, as shown in Fig. 4, thereby leaving openings in 35 the side walls of the carton. The base lines 26 by which the auxiliary cross partitions are hinged to the outer walls of the carton preferably are of substantial width so as to provide adequate strength. The auxiliary cross partitions 24 and 40 25 are provided with hook members 27 adjacent their free ends to secure the auxiliary cross partitions in position. These hook members are interlocked with the bottom and longitudinal partition-forming sections 13 and 14 at the opening 45 28 therein, as will be seen from Figs. 1 and 4.

It will be noted that the auxiliary cross partitions are positioned in such a manner as to offer substantial protection for eggs in the end cells of the broken away carton. The hooks on the auxiliary cross partitions are shown to engage the longitudinal partition of the carton in a somewhat rigid manner, thereby stabilizing the end structure of the container. In particular, it will be noted that the hook elements of the 55

auxiliary cross partitions face in a direction opposite the hook elements 21 on the principal cross partitions.

The invention has been described with particular reference to a certain type of egg carton, but it will be readily understood that it may be employed with many other cartons now well known in the trade. For example, the hook members of the auxiliary cross partitions may be engaged with a separate longitudinal partition. The various changes which may be made in the structure without departing from the scope of the invention are intended to be included in the appended claims.

15 I claim:

1. A cellular carton of the type described, comprising front and rear walls, a longitudinal partition, a series of cross partitions hinged to said walls, said walls having a weakened portion for 20 division of the carton into more than one portion,

and auxiliary cross partitions adjacent the weakened portion of said walls and struck from the material thereof, said auxiliary cross partitions being engageable with said longitudinal partition.

2. A cellular carton of the type described, comprising front and rear walls, a bottom and longitudinal partition-forming section joining said walls and extending in substantially inverted V-shape, cross partitions hinged to the upper portions of said walls and having hooked members 5 engaged with said bottom and longitudinal partition-forming section, said walls and said bottom and longitudinal partition-forming section being weakened adjacent one of said cross partitions, and auxiliary cross partitions struck from 10 said front and rear walls adjacent said weakened portion and having hooked members for engagement with said bottom and longitudinal partition-forming section. 15
